United States Patent Office

Des. 225,709
Patented Jan. 2, 1973

225,709

CHECK STAND DIVIDER

Don Pace, West Covina, Calif., assignor to Pacific Handy Cutter Incorporated, El Monte, Calif.

Filed Feb. 5, 1971, Ser. No. 113,117

Term of patent 14 years

Int. Cl. D6—06

U.S. Cl. D6—191

FIG. 1 is a perspective view showing my new design for a check stand divider with one display strip partially removed;

FIG. 2 is another perspective view thereof with the strips in place; and

FIG. 3 is an end elevational view thereof.

I claim:

The ornamental design for a check stand divider, as shown and described.
